(57) **CLAIM**

The ornamental design for a perch, as shown and described.

DESCRIPTION

FIG. 1 is a top perspective view of a perch in accordance with our new design, shown illustratively in conjunction with a bird feeder;

FIG. 2 is a bottom perspective view thereof.

FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof.

FIG. 9 is a top perspective view thereof without the bird feeder shown; and,

FIG. 10 is a bottom perspective view thereof without the bird feeder shown.

The broken lines shown in the Figures are environment only that form no part of the claimed design.

(Continued)

US D921,998 S

Page 2

The shade lines in the Figures show contour and do not claim surface ornamentation or treatment.

1 Claim, 8 Drawing Sheets
